(57) **CLAIM**

The ornamental design for an electrophoresis and imaging system display screen with graphical user interface, as shown and described.

DESCRIPTION

FIG. 1 is a view of a first embodiment of an electrophoresis and imaging system display screen with graphical user interface of our new design.

FIG. 2 is a view of a second embodiment of an electrophoresis and imaging system display screen with graphical user interface of our new design.

FIG. 3 is a view of a third embodiment of an electrophoresis and imaging system display screen with graphical user interface of our new design; and,

FIG. 4 is a view of a fourth embodiment of an electrophoresis and imaging system display screen with graphical user interface of our new design.

The broken line showing of a display screen and portions of a graphical user interface is included for the purpose of illustrating portions of the article and forms no part of the claimed design.
